Frank Edward Mors

UNITED STATES PATENT OFFICE.

FRANK EDWARD MORS, OF DETROIT, MICHIGAN.

NAILLESS COMBINATION WINDOW SHADE AND CURTAIN HANGER.

1,216,592.

Specification of Letters Patent. Patented Feb. 20, 1917.

Application filed July 20, 1916. Serial No. 110,326.

To all whom it may concern:

Be it known that I, FRANK EDWARD Mors, a citizen of the United States, residing at Detroit, county of Wayne, and State of Michigan, have invented a Nailless Combination Window Shade and Curtain Hanger.

This invention relates to a combination window shade and hanger, and the primary object of my invention is to provide an adjustable window frame fixture that can be easily and quickly placed in position to support curtain shade rollers and curtain poles, without resorting to nails, screws, tacks or similar fastening means for holding the fixture in position, thus not marring or disfiguring a window frame.

Another object of the invention is to provide a window fixture which can be easily and quickly adjusted and clamped between the stiles of a window frame, to support curtain shade rollers or a curtain pole at a desired elevation relative to window sashes.

A further object of my invention is to provide a simple, durable and inexpensive fixture of the above type consisting of comparatively few parts that are easy to assemble and highly efficient for the purposes for which they are intended.

The above and other objects are attained by a mechanical construction that will be hereinafter described, and reference will now be had to the drawing, wherein—

Figure 1 is a cross sectional view of the fixture in position relative to a window frame;

Fig. 2 is a perspective view of a portion of the fixture;

Fig. 3 is a plan of the fixture, partly broken away and partly in section, and

Fig. 4 is a cross sectional view, taken on the line A—B of Fig. 3.

In the drawing, 4 denotes longitudinally alining fixture members that may be made of wood, metal or any suitable material. These members are preferably rectangular in cross section and have the confronting ends thereof provided with longitudinal bores 9 in which are mounted sleeves 10 and 11, the former being interiorly screwthreaded and the walls of the latter smooth. Adjustable in the threaded sleeve 10 is a screw

12 having a smooth end 13 rotatable in the sleeve 11 and on said screw is a nut 5 abutting a washer 14 against the end of the sleeve 10. Encircling the screw 12, between the nut 5 and the end of the sleeve 11 is a coiled compression spring 8. The expansive force of this spring tends to hold the fixture members separated.

Closing the gap between the confronting ends of the fixture member 4 is a shiftable sleeve 6 and this sleeve may be shifted on to either of the fixture members 4 when it is desired to adjust the nut 5 and further separate the fixture members 4.

The outer ends of the fixture members 4 are provided with pads or blocks 7, preferably of rubber, felt or yieldable material and these pads or blocks are adapted for engagement with the stiles 15 of a window frame, without disfiguring or injuring the finish of the stiles.

The lower faces of the fixture members 4 are provided with angle brackets 3 adapted for supporting a curtain shade roller 16 in the usual and well known manner and side faces of the fixture members 4 are provided with Z-shaped brackets 2 adapted for supporting a curtain shade roller 17. Adjacent the brackets 2 are the inner fixed ends of bracket arms 1 adapted for supporting a curtain pole 18, and as a result of this construction the outer and inner curtain shade rollers may be supported in front of a window frame with curtains or portières in front of the inner curtain shade roller 17.

As shown in Fig. 1, the fixture members 4 may be placed in the extreme upper part of a window frame against the lintel thereof and the relative position of the curtains is such that each may be easily and individually adjusted.

One embodiment of my invention has been illustrated but it is to be understood that the structural elements are susceptible to such variations and modifications as fall within the scope of the appended claim.

What I claim is:—

A fixture of the type described, comprising longitudinally alining members with a gap therebetween, sleeves mounted in the confronting ends of said members, an ad-

justable screw in one of said sleeves having a smooth end extending into the other of said sleeves, a spring encircling said screw between the ends of said members and adapted to hold said members separated, a shiftable sleeve slidable on said members and adapted to close the gap therebetween, cur-

tain shade roller brackets carried by the lower faces of said members, curtain shade roller brackets carried by side faces of said members, and curtain pole bracket arms carried by side faces of said members.

FRANK EDWARD MORS.
